H. H. HANSARD

WRIST SUPPORT

Filed Aug. 25, 1921

FIG. 1

FIG. 2

Inventor
Hugh H. Hansard

By
A. L. Herstovkaugh & Co
Attns.

UNITED STATES PATENT OFFICE.

HUGH H. HANSARD, OF MONTREAL, QUEBEC, CANADA.

WRIST SUPPORT.

Application filed August 25, 1921. Serial No. 495,255.

To all whom it may concern:

Be it known that I, HUGH H. HANSARD, a subject of the King of Great Britain, and resident of the city of Montreal, in the 5 Province of Quebec and Dominion of Canada, have invented certain new and useful Improvements in Wrist Supports, of which the following is a full, clear, and exact description.

10 This invention relates to improvements in wrist supports, and the object of the invention is to provide means for supporting a wrist against bending backward and forward while yet leaving it free if desired to 15 bend sideways.

A further object is to provide a support of this type particularly adapted for use by persons playing golf, billiards or other games in which a back and forth movement 20 of the wrist continues a defective action.

A still further object is to arrange the support within a glove, so that there will be nothing unusual or unsightly about the appearance of the apparatus.

25 The invention comprises the provision of a pair of slightly resilient but withal comparatively stiff members of material, such as spring steel, located against the back and front of the wrist and hand and held to the hand and forearm adjacent the wrist joint either rigidly or by such slip connection as will permit edgewise movement of the hand 30 from the wrist.

In the drawings which illustrate the invention:—

35 Fig. 1 is a side view illustrating the device in position on a hand.

Fig. 2 is a front or palm view of the apparatus.

40 Referring more particularly to the drawings, 11 designates a glove with a comparatively long wrist portion 12 open in the usual manner. Within the glove there is provided a member 13 and possibly an additional member 14 of stiff but slightly resilient material, such as spring steel. These members are designed to lie against the back and front of the hand, as illustrated in Figure 1, and are suitably curved to hold the

hand in any desired position with relation to 50 the forearm, for example, the slightly bent back position shown in Figure 1. The forward ends of these members are held against the wearer's hand by the glove itself which may be suitably reinforced as indicated at 55 15. Furthermore, a complete or partial covering 16 may be provided for the members 13 and 14 to limit the movement thereof or to hold the same away from close contact with the wearer's hand. This separating strip 16 is especially to be desired where edgewise movement of the hand is permissible, as it separates the supporting members 13 and 14 from the hand and enables the hand to move easily relatively to the 60 member or members. The rear ends of the supporting members 13 and 14 are held to the wearer's forearm at a suitable distance from the wrist joint by a strap or band 17 suitably incorporated with the glove and 65 preferably having a fastening means 19, which may be concealed within the wrist of the glove but to which access may be had by opening the wrist of the glove. As with the forward ends of the supporting members, a shield 18 may be provided at the 70 wrist between the supporting members and the wearer's skin. In addition to the separating members 16 and 18, the supports may be covered with leather, fabric or other suitable material (not shown). The supporting members may be additionally attached to the glove, for example, by one or more rivets 75 20 located intermediate the ends of the members or may be entirely separate and removable from the glove. When only a single rivet is used, as indicated, it will serve 80 as a pivot upon which the supporting member may swing to give freedom of movement to the hand in the edgewise direction. 85 On the contrary, either end of a supporting member may be rigidly attached either to the glove or to the wearer, so that the hand 90 will have only a limited edgewise movement. Naturally, if the supporting members are 95 rigidly attached to the glove throughout their length, they will prevent edgewise movement of the wearer's hand. In this

respect, the construction will be according to the results desired. The members 13 and 14 may be initially formed to suitable peripheral shape and curvatures or may be supplied in substantially flat form with a view to being bent to the desired curvature by the user.

It is obvious that the supporting members, being strapped tightly to the palm of the hand and to the forearm above the wrist, will hold the hand from swinging forwards or backwards but will hold it at any angle to the arm, for which the supports are formed. The hand may be permitted either free or limited edgewise movement, as illustrated in Figure 2, or if the supports are rigidly attached to the glove the hand will also be held against such movement and will be rigid with the arm in all directions. Preferably, however, the hand is permitted an edgewise movement as this is the movement really used in imparting motion to a billiard cue for example. The device may be worn either as a permanent aid or merely temporarily until a person learns the correct position at which to hold the hand for any desired result. The apparatus may also be used to give stiffness and strength to weak wrists and, for this purpose, the supports may be much less rigid than would otherwise be the case. Obviously, the invention is not limited to holding the hand in the bent back position illustrated in Figure 1 but applies equally to all positions. No attempt has been made to illustrate the various peripheral forms and curvatures in which the supports may be made, as these will vary according to the use to which the support is to be put. It will be understood, therefore, that the invention is not limited to the comparatively narrow parallel-sided strips shown, as these strips may assume other shapes and, if wider, may be curved to conform to the hand even to the point of embracing the hand and thus in a measure usurp the functions of the straps 15 or 17. For certain purposes, the single member 13 will be found sufficient so that the invention is not limited to the use of two supports. It will further be understood that the supports may take such form that they can be secured to the hand entirely independent of a glove, and be thus available for concealment by an ordinary glove and so avoid the expense of a special glove.

Having thus described my invention, what I claim is:—

1. A device of the class described, comprising a pair of supporting members of limited resiliency formed to lie against the back and front respectively of a hand and forearm to hold the hand against forward and backward movement, and means for securing said members to the hand and fore-

arm adapted to permit limited movement of the supports therein to enable edgewise movement of the hand relatively to the arm.

2. A wrist support comprising a comparatively stiff supporting member formed to lie against the hand and forearm, means for securing said member to the hand and forearm, and separators interposed between the supporting member and the hand and forearm to facilitate permissible relative movement of the hand and supporting member.

3. A wrist support comprising a stiff supporting member formed to lie against the hand and forearm, means for securing said member to the hand and forearm and a glove for the hand and forearm enclosing and concealing the supporting member.

4. A wrist support comprising a stiff supporting member formed to lie against the hand and forearm and a glove enclosing and concealing the supporting member and constituting the means for attaching the supporting member to the wearer's hand.

5. A wrist support comprising a glove for enclosing the hand and forearm, and a supporting means secured within the glove to lie against the hand and forearm and movable relatively to the glove to permit of an edgewise movement of the hand.

6. A wrist support comprising a glove for enclosing the hand and forearm, and a supporting means secured within the glove to lie against the hand and forearm and movable relatively to the glove and to the hand and forearm to permit of an edgewise movement of the hand.

7. A wrist support comprising a glove for enclosing the hand and forearm, a supporting member secured within a glove formed to lie against the hand and forearm and to hold the hand slightly out of the plane of the arm, said supporting member being completely concealed within the glove and movable relatively thereto to permit of an edgewise movement of the hand.

8. A wrist support comprising a glove for enclosing the hand and forearm, a supporting means concealed within the glove and formed to lie against the hand and forearm, and means for holding the glove and supporting member in place adapted to permit of edgewise movement of the hand relatively to the supporting member.

9. A wrist support comprising a glove for completely enclosing the hand and forearm, supporting means concealed within the glove and formed to lie against the hand and forearm, and means for securing the glove and supporting means in place.

10. A wrist support comprising a comparatively stiff supporting member engageable with the hand and forearm and means for holding the supporting member to the hand and forearm in relatively movable re-

lation therewith whereby the hand may be moved laterally with respect to the supporting member.

11. A wrist support comprising comparatively stiff supporting members engageable with the back and front respectively of a hand and forearm to hold the hand against backward and forward movement, and

means for holding the supporting members to the hand and forearm in relatively movable relation therewith whereby the hand may be moved laterally between said supporting members. ¹⁰

In witness whereof, I have hereunto set my hand.

HUGH H. HANSARD.
